PLASTIC COVER FOR A CONTAINER

Douglas L. Jocelyn, Birmingham, Mich., assignor to Plastray Corporation, Detroit, Mich., a corporation of Michigan

Application June 4, 1956, Serial No. 41,754

Term of patent 7 years

(Cl. D58—26)

Fig. 1 is a top plan view of a plastic cover for a container embodying my invention.

Fig. 2 is a side elevation thereof.

Fig. 3 is a fragmentary cross sectional view taken centrally through Fig. 1 with the lid of the plastic cover in open position.

I claim:

The ornamental design for a plastic cover for a container, substantially as shown.
